UNITED STATES PATENT OFFICE.

MATTHEW G. O'NEIL, OF DALLAS, TEXAS, ASSIGNOR, BY MESNE ASSIGNMENTS, TO STANDARD VENDING CORPORATION, OF WILMINGTON, DELAWARE, A CORPORATION OF DELAWARE.

VENDING MACHINE.

Application filed December 3, 1920, Serial No. 427,966. Renewed July 29, 1926.

The invention relates to an improvement in vending machines of the type wherein small articles, such as chewing gum, candy and the like, are delivered from the machine 5 upon the insertion of a coin therein and the manipulation of a lever or plunger.

One object of the invention is to improve upon the construction and arrangement of the parts constituting a machine of this 10 character in order to produce a more simple, durable and efficient machine. Other objects of the invention will appear as the description proceeds. With these objects in view, the invention consists in the improved 15 vending machine hereinafter described and particularly pointed out in the appended claims.

The preferred form of the invention is illustrated in the accompanying drawings 20 in which Fig. 1 is a rear elevation of the improved vending machine with the back cover removed and other parts broken away to disclose the operating mechanism; Figs. 2 and 3 are vertical sections taken on the lines 25 2—2 and 3—3, respectively, of Fig. 1; Fig. 4 is a front elevation on a reduced scale; Figs. 5 and 6 are detail views illustrating different positions of the plunger and the slide; Fig. 7 is a front elevation of the tray 30 for holding the articles to be vended; and Fig. 8 is an end elevation of the tray.

In the illustrated embodiment of the invention the operating parts of the improved vending machine are shown as enclosed in a box or cabinet 1 having a front plate 2 35 which is removable for the purpose of inserting the gum, candy or other articles to be vended and for giving access to the operating mechanism. This plate is provided 40 with the vertically and horizontally arranged windows 3 and 4 for displaying the merchandise.

The operating mechanism for delivering the article upon the insertion of a coin of the 45 proper size and weight comprises a vertically arranged reciprocating slide 5 and a vertically arranged reciprocating plunger 8 having a finger piece 9 projecting downwardly below the bottom of the box. The plunger is adapted to be operatively connected with the slide by the interposition of

a coin, as shown in Fig. 6. The slide 5 is provided with a laterally and downwardly projecting arm 6, the lower part of which is provided with a slot 7 in which is loosely 55 engaged a lug 28 projecting rearwardly from a pivotally mounted tray or cradle 14 for supporting the pile of articles to be vended. The plunger 8 is provided with spaced, upwardly projecting lugs or fingers 60 10 which are adapted to receive a coin 25 of proper size and weight and lift it into contact with the slide 5, whereby the arm 6 is raised to tilt the tray 14 to deliver therefrom the lowermost article 29. The slide 5 65 and the plunger 8 are held in operative position by the guides 19 and 20.

The box or cabinet 1 is divided into three compartments. The front or largest compartment, indicated at 13, serves as a magazine in which the gum, candy or other articles are stored, the lowermost article 29 resting upon the tray or cradle 14. The second or middle compartment 15 serves as a coin slot through which a coin of proper 70 size and weight passes into the operating parts of the machine through a coin chute 26. This compartment is formed by the back plate 16 of the magazine and a cover plate 17. The third or rearmost compartment 18 is formed between the cover plate 17 and the rear wall of the box or cabinet 1. The slide 5 and plunger 8 operate in the compartment 18. In the lower part of the front compartment 13 there is a projecting 75 shelf 21 having a curved bottom 22. The shelf 21 acts as a baffle to prevent the insertion of an implement for tampering with the mechanism and the curved bottom 22 acts as a chute to deliver the article which 80 has been discharged from the tray 14.

When a coin 25 is in position between the upwardly projecting lugs 10 of the plunger 8, and the plunger is raised to bring the coin into contact with the lower curved edge of the slide 5, the coin passes under the inwardly curved upper edge of a flat spring 27 which serves as a deflector to deflect the coin into the coin receptacle. As the arm 6 is lifted with the slide 5 it is disengaged from 95 a lever 30 and thereby permits a spring 32 to push a bolt 31 (which the lever normally 100

holds in inoperative position) into engagement with the plunger 8. In the plunger 8 is a notch 33 in which the end of the bolt 31 is adapted to be received to prevent the 5 plunger from returning to normal or inoperative position until after the plunger has been pushed upwardly far enough to cause the coin to pass beyond the upper edge of the deflector 27. When the coin reaches this 10 point, a coiled spring 34 draws the slide 5 back to its normal position and at the same time ejects the coin through the arched part 35 over the top of the deflector 27 from which point the coin falls on the beveled 15 shelf 7^a and thence into the coin tray 36 located in the bottom of the compartment 18. As the arm 6 returns to normal position with the slide 5 it contacts with the lever 30, thereby disengaging the bolt 31 from the 20 notch 33 to permit the plunger to return to normal position.

The tray or carrier 14 is not tilted far enough to deliver the lowermost article from the machine until the plunger has been 25 pushed upwardly far enough to cause the bottom of the coin to pass the inturned lip or stop 38^a formed at the port or slot 37 in the plate 16. When the coin has reached 30 and passed this point it cannot be reused with another manipulation of the plunger. Moreover, the locking of the plunger by the bolt 31 will prevent additional coins from 35 entering the space between the lugs or fingers 10, as is clearly shown in Fig. 6. Before the plunger can return to normal position to permit the next coin to fall into place between the lugs or fingers 10 the plunger must have been raised to the limit of its upward movement. It will be obvious that if there is 40 more than one coin in the coin chute 26 when the plunger is raised, the right hand lug or finger 10 will push the second coin back into the chute again. This mechanism cooperates with only a single coin at each upward 45 movement of the plunger 8 to deliver the article. The tilting of the tray or cradle 14 sufficiently far to deliver the lowermost article 29 therefrom takes place substantially at the time the bottom of the coin passes beyond the upper inturned edge of the deflector 27. As the tray is tilted, the inturned fingers or lugs 13^a pass under the lowermost article 29 of the pile or column 30^a and hold the pile until the downward movement of 55 the arm 6 returns the tray to normal position. Thereupon the lugs 13^a release the pile, which then settles down on the bottom of the tray.

In order to prevent slugs and other spurious coins from passing into the coin chute 26, a peculiarly shaped magnet 23 is located in the upper part of the coin compartment 15. If the slug is composed of iron, steel, or other metal affected by magnetism, it will be 60 attracted by the magnet, and as it falls under

the action of gravity, it will be carried by the lower arm 23 of the magnet to a point where it will drop on to the deflector 38 and pass into the coin tray 36. If the coin is under weight, or if it is composed of some 70 material unaffected by magnetism, it will pass by the magnet and fall upon the lever 24 (located below and to one side of the magnet), and be deflected thereby on to the deflector 38 and thence it will pass into the coin 75 tray 36. If the coin 25 is of proper size and weight, it will tilt the lever 24, overcoming the weighted arm 24^a thereof, and be deflected thereby into the coin chute 26, from 80 which it will pass to the position shown in Fig. 5.

If the coin or slug is composed of a material unaffected by magnetism, and is heavy enough to overcome the weighted arm 24^a of the lever 24 so as to pass into the coin chute 85 26, and yet is under size, it will fall down between the lugs or fingers 10, these fingers being spaced apart sufficiently far to permit the plunger 8 to raise only full sized coins against the slide 5. To prevent the undersized coins from sticking between the sliding parts, the lower rear edge of the plate 16 is provided with a projecting guide or deflector 39 which cooperates with the beveled 90 edge 12 on the plunger 8 to deflect the undersized coin into the coin tray 36. In order to 95 permit the plunger 8 to pass freely by the guide 39 the front surface of the plunger is provided with a vertically arranged groove 100 11.

The mode of operation of the machine has been indicated in connection with the specific description of the construction and mode of operation of the various parts of the operating mechanism. It is sufficiently recapitulated as follows:—It is assumed that a coin 25, of proper size and weight, has been deposited in the coin slot 15 and that it has tilted the lever 24 and passed through the coin chute 26 into the position shown in 110 Fig. 5, between the upper edges of the fingers 10 of the plunger 8. The raising of the plunger brings the coin in contact with the slide 5 to raise the arm 6 and thereby tilt the tray 14. The upward movement of 115 the arm 6 releases the lever 30 to permit the bolt 31 to engage the plunger 8 and prevent it from returning to normal position until after the coin has passed the inturned upper edge of the deflector 27. The tray is not tilted far enough to deliver the lowermost article 29 therefrom until the bottom of the coin has passed the inturned stop 38^a. When the coin has passed this point, the plunger cannot return to normal position. 120 Thus the plunger must be pushed to the limit of its upward movement to deliver the goods and at the same time raise the coin far enough to cause it to pass beyond the deflector 27 by which it will be deflected into 125 130

the coin tray 36 by the action of the spring 34 seeking to return the slide 5 to normal position. When the coin has been deflected from the deflector 27, the slide 5 and arm 6 return to normal position, at the same time returning the tray 14 to normal position and permitting the pile of goods to settle down on its bottom. The return of the arm 6 to normal position causes the lever 30 to again lock the bolt 31 and permit the plunger 8 to return to normal position. The machine is now in condition to be operated again.

Having thus described the invention, what I claim as new is:—

1. A coin-controlled vending machine having, in combination, a tilttable tray to support the articles to be vended, a slide connected with the tray, a plunger adapted to be operatively connected with the slide by a coin, a coin deflector interposed in the path of travel of the coin while on the plunger, a bolt adapted to cooperate with the plunger to prevent the return of the plunger to normal position until after the coin has passed the deflector, and means controlled by the upward movement of the plunger for moving the bolt out of engagement with the plunger when the coin has passed beyond the deflector.

2. A coin-controlled vending machine having, in combination, a tray for supporting the articles to be vended, a slide connected with the tray to actuate it to deliver the article resting on the tray, a plunger adapted to be operatively connected with the slide by a coin, a spring for returning the slide and tray to normal position, a coin deflector interposed in the path of travel of the coin while it is on the plunger, and means controlled by the upward movement of the plunger for preventing the return of the plunger to normal position until after the coin has passed beyond the deflector.

3. A coin-controlled vending machine having, in combination, a tray for supporting the articles to be vended, a slide connected with the tray, a plunger adapted to be operatively connected with the slide by a coin, a stop projecting into the path of travel of the coin while on the plunger to prevent its return, the parts being arranged so that the tray does not deliver the article resting thereon until the coin passes the stop, a coin deflector projecting into the path of travel of the coin, and means for preventing the return of the plunger to normal position after the coin has passed the stop until the coin has passed beyond the deflector.

4. A coin-controlled vending machine comprising a tilttable tray to support the articles to be vended, an actuated part connected with the tray, a plunger adapted to be operatively connected with said actuating part by a coin, means for disconnecting

the coin from the plunger when the plunger is moved, a bolt adapted to cooperate with the plunger to prevent the return of the plunger to normal position until after the coin has been disconnected therefrom.

70

5. A coin-controlled vending machine having, in combination, a tray for supporting the articles to be vended, a vertically arranged reciprocating slide connected with the tray to actuate it to deliver the article resting thereon, a vertically arranged reciprocating plunger adapted to be operatively connected with the slide by a coin, a stop in the path of travel of the coin while it is on the plunger, a deflector interposed in the path of travel of the coin, and means for preventing the return of the plunger to normal position after the coin has passed the stop and until after the coin has passed beyond the deflector.

80

85

6. A coin-controlled vending machine having, in combination, a tray for supporting the articles to be vended, a vertically arranged reciprocating slide connected with the tray to actuate it to cause it to deliver the article resting thereon, a vertically arranged reciprocating plunger adapted to be operatively connected with the slide by a coin, a coin deflector interposed in the path of travel of the coin while it is on the plunger, and means controlled by the slide for preventing the return of the plunger to normal position until after the coin has passed beyond the deflector.

90

95

7. A coin-controlled vending machine having, in combination, a tilttable tray for supporting the articles to be vended, a vertically arranged reciprocating slide connected with the tray to actuate it to deliver the article resting thereon, a vertically arranged reciprocating plunger adapted to be operatively connected with the slide by a coin, a coin deflector interposed in the path of travel of the coin while it is on the plunger, a notch in the plunger, a bolt adapted to be engaged in the notch to prevent the return of the plunger to normal position until after the coin has passed beyond the deflector, and means controlled by the slide for disengaging the bolt from the plunger when the slide has returned to normal position.

100

105

110

115

8. A coin-controlled vending machine having, in combination, a tilttable tray for supporting the goods to be vended, a vertically arranged reciprocating slide connected with the tray, a vertically arranged reciprocating plunger adapted to be operatively connected with the slide by a coin, a coin chute above the plunger to deliver a coin thereto, a coin deflector interposed in the path of travel of the coin while it is on the plunger, means for returning the parts to normal position when the coin has passed the deflector, and means controlled

120

125

130

by the slide for preventing the plunger from returning to normal position until after the coin has passed beyond the deflector.

9. A coin-controlled vending machine having, in combination, a tray for supporting the articles to be vended, means for actuating the tray to deliver the article resting thereon, a plunger adapted to be operatively connected with the tray actuating means by a coin, a stop interposed in the path of travel of the coin while it is engaged by the plunger to prevent the return of the coin, the parts being arranged so that the tray is not actuated sufficiently to deliver

the article thereon until the coin has passed 15 the stop, a deflector in the path of travel of the coin, means for preventing the return of the plunger to normal position until after the coin has passed the deflector, the downward movement of the plunger acting to 20 deflect the coin into a coin receptacle and permit the return of the parts to normal position when the coin has passed beyond the deflector.

In testimony whereof I have signed my 25 name to this specification.

MATTHEW G. O'NEIL.
